UNITED STATES PATENT OFFICE

MILDRED LEE, OF SANTA MONICA, CALIFORNIA

DESIGN FOR A TOY

Application filed May 13, 1930. Serial No. 35,625. Term of patent 3½ years.

To all whom it may concern:

Be it known that I, MILDRED LEE, a citizen of the United States, residing at Santa Monica, in the county of Los Angeles and State of California, have invented a new, original, and ornamental Design for a Toy, of which the following is a specification, reference being had to the accompanying drawing, forming a part thereof and in which,

Figure 1 is a front view,
Fig. 2 is a rear view, and
Fig. 3 a side view.

I claim:

The ornamental design for a toy as shown.

MILDRED LEE.
